DESIGN FOR A BEVERAGE PERCOLATOR FILTER VALVE

Ernest L. Lilja, Chicago, Ill., assignor to Chamberlain, Inc., Chicago, Ill., a corporation of Illinois

Application November 28, 1947, Serial No. 142,841

Term of patent 14 years

(Cl. D44—26)

To all whom it may concern:

Be it known that I, Ernest L. Lilja, a citizen of the United States, residing at Chicago, in the county of Cook and State of Illinois, have invented a new, original, and ornamental Design for a Beverage Percolator Filter Valve, of which the following is a specification, reference being had to the accompanying drawing, forming a part thereof.

Fig. 1 is an elevational view of a beverage percolator filter valve, showing my new design; and Fig. 2 is a bottom plan view thereof.

I claim:

The ornamental design for a beverage percolator filter valve, as shown.

ERNEST L. LILJA.
